METHOD AND MECHANISM FOR PRODUC-
ING KNITTED FABRICEmil Richter, West Lawn, Pa., assignor to Textile
Machine Works, Wyomissing, Pa., a corpora-
tion of Pennsylvania

Application September 16, 1932, Serial No. 633,531

31 Claims. (Cl. 66—96)

This invention relates to a textile knitting machine and has for one of its objects a design of knitting machine that is capable of knitting plain fabric, lace design fabric, non-run fabric or fabric having one or more barrier courses of a more effective construction than barrier courses heretofore produced.

Another object of the invention resides in redesigning and associating component parts of a stocking knitting machine to enable the same to interlock various loops of the stocking in the knitting thereof to provide any number of barrier courses which collectively may be utilized to provide barriers against "runs" in the stocking or to produce a lace effect or to produce a stocking "run proof" throughout.

Another object of the invention resides in the provision of a simplified type of attachment that may be applied to well known constructions of stocking knitting machines to enable the same to more effectively produce spread interlocking loops.

Another object of the invention resides in the combination of mechanisms including a novel type of point mechanism whereby a hosiery knitting machine is capable of selectively knitting plain fabric, lace fabric or non-run fabric having any predetermined number of barrier courses, each of a design to positively prevent runs from extending in either direction in the fabric.

Another object of the invention resides in the introduction of novel devices in the construction of a full fashion hosiery knitting machine that will enable the progressive forming of plain courses and interlocking courses, the interlocking courses being produced by spreading and interlocking predetermined loops with associated loops thereby preventing unraveling in case predetermined loops break.

40 A feature of my invention resides in the novel manner of relating cofunctioning mechanisms whereby the same may operate in required time relations to form any number of courses of plain loops and any number of courses of barrier or interlocking loops.

Besides the above my invention is distinguished in the use of a novel type of point mechanism which, after the needle mechanism has formed a course of regular stitches as loops, lifts predetermined loops from the needles and spreads or reshapes the predetermined loops independent of the needle mechanism of the knitting machine thereby enabling me to control that particular course in the fabric in which the spread or reshaped loops will be arranged.

My invention is also distinguished in supporting and spreading the above mentioned lifted loops in suspended positions independent of the needles thereby enabling me to time the depositing of the spread loops upon predetermined needles.

With these and other objects in view the invention will be better understood from the following detail description taken in connection with the accompanying drawings, wherein:

Fig. 1 is a front elevation of the machine.

Fig. 2 is an end elevation.

Fig. 3 is a cross sectional view taken along the line 3—3 of Fig. 1, with certain parts omitted for the sake of clarity.

15 Fig. 35 is a cross sectional view on the line 35—35 of Fig. 33.

Fig. 36 is a sectional view on the line 36—36 of Fig. 33.

20 Fig. 37 is a cross sectional view on the line 37—37 of Fig. 34.

Fig. 38 is a diagrammatic view illustrating one of the relative positions of the points and needles.

Fig. 39 is a diagrammatic view of another relative position of the points and needles.

25 Fig. 40 is a diagrammatic view of a third relative position of the points and needles.

Referring to the drawings, there is shown a preferred form of my machine which is constructed so as to utilize certain parts and groups of devices 30 commonly used on a Reading type of full fashioned hosiery knitting machine, certain known parts and devices having been omitted for the sake of clearness. Therefore, my invention is illustrated basically as consisting of a frame A; 35 power mechanism B; pattern control mechanism C; carrier and narrowing motion mechanism D; needle mechanism E; sinker and divider mechanism F; and point mechanism G.

Referring to Figs. 30, 31 and 32, it will be noted 40 that the fabric from which the stocking 1 is produced is knitted in a manner to provide plain courses 2 and interlocking or barrier courses 3, the interlocking courses in this particular showing alternating with the plain courses, but I wish it to 45 be understood that any number of plain courses may be used between any particular number of interlocking courses and further any number of interlocking courses may be utilized throughout the stocking which requires only repeating of the 50 machine operations hereinafter described to successfully produce any required number of interlocking courses. The plain courses are formed from plain loops 4, whereas each interlocking or barrier course consists of plain loops 5 alternating 55 with spread interlocking loops 6. At this point I wish to call attention to the fact that if found desirable in practice, every loop of the interlocking course may be formed as a spread or interlocking loop, but I have found from extensive investigations that increased elasticity can be accomplished by alternating plain loops with 60 spread loops and besides the fabric is given a more uniform appearance. In producing the interlocking or barrier courses, I first form a course of plain loops and then selected loops, 65 preferably alternate loops are each spread from the wale in which they originate to an adjacent wale, the bight portion 7 of the spread loop engaging under a needle loop and over an associated 70 sinker loop so that the bight 7 will be gripped between the needle wale loop and a sinker wale loop as clearly shown in Fig. 31. In the spreading of each interlocking loop, I have found it of great advantage to spread the loop independently 75 of the needles of the knitting machine so as to

accomplish a more easy spreading of the loop and the proper shaping of the same to quickly and effectively engage over the required number of needles of the knitting machine.

In Fig. 31 it will be noted that I have illustrated 5 two interlocking or barrier courses between which is arranged a plain course whereas in Fig. 32 I have illustrated three barrier courses alternating with plain courses and I wish to be understood that this may be repeated throughout the 10 entire area of the fabric. I also wish to call attention to the fact that the spread loops of one barrier course are arranged in alternate positions 15 in relation to the spread loops of associated barrier courses so as to positively prevent "runs" from 20 extending upwardly or downwardly of the stocking. I am aware of the fact that transferred loops have been utilized heretofore to form barrier courses but such a barrier course only prevents the passage of a "run" downwardly of the 25 stocking and will not prevent a "run" from passing upwardly of the stocking. I am also aware of the fact that various designs of spread loops have been used for ornamenting a fabric and therefore I am not attempting to claim any particular type of fabric, the present invention relating solely to a novel construction of knitting machine for economically producing a stocking having "non-run" properties either in a restricted 30 area or over the entire area of the stocking. 30

Frame A

This frame consists of front and back beams 3 and 9, front and center beds 10 and 11 and a plurality of frames 12. 35

Power mechanism B

The power mechanism B consists of a main power shaft 13 which is adapted to be rotated by a prime mover such as an electric motor and 40 to be shifted longitudinally by a shifttable device 14 in a manner hereinafter described. This shaft 13 has mounted thereon a main point cam 15, an auxiliary point cam 16, a needle cam 17, pattern cams 18 and 19 and a narrowing cam 20. 45 Of course, it is to be understood that there are other cams besides those set forth that are attached to the shaft 13 in the completed full fashion machine for accomplishing all of the variations in knitting necessary on a modern type of 50 knitting machine. 50

Pattern motion mechanism C

The pattern motion mechanism C is practically 55 the same type of mechanism now used on the Reading type of knitting machine with slight modifications and involves basically a lace attachment 21 and a control attachment 22, the two cofunctioning to control the action of the 60 complete knitting machine and the latter further controlling the action of the shifting device 14 for periodically shifting the shaft 13 in the usual manner when the knitting machine is performing a narrowing operation. The control attachment 22 consists basically of the usual instrumentalities designated as a group by the numeral 23 and the lace attachment 21 consists of the usual instrumentalities designated as a group 65 by the numeral 24, both sets of attachments being illustrated in the Reading Full Fashioned 70 Knitting Machine Catalogue, copyright 1929, and in a supplement thereto entitled "Lace clock attachment" dated February 1, 1932, published by Textile Machine Works, Reading, Pa. Included 75 in the instrumentalities 24 of the lace attachment

21 is a lever 25 operated periodically by the pattern cam 18 on the cam shaft 13 through its engagement with a roller 26 carried by the lever 25. This lever 25 has a link connection 27 with 5 a slidably mounted cam block 28 positioned to operate the novel point mechanism hereinafter described by the inclined cam surface 28b thereof. The instrumentalities 24 also include a lever 29 having a roller 30 arranged in shiftable relation with the pattern cam 19 and this lever 29 is provided with an arm 31 which is an addition to the usual lace attachment. This arm 31 is connected to a link 32 that is operatively connected to a cam member 33 which constitutes 10 one element of a novel type of point rod actuating device 34, the other member 35 of which carries a roller 36 cofunctioning with the cam surface 28b of the cam block 28 for shifting the device 34 horizontally in two separate movements, the member 33 being capable of independent vertical movement relative to the cam member 35 in a manner hereinafter described. Attention is called to the fact that the design of the lace attachment is such that the operation of 15 the knitting machine may be selectively controlled to enable the various mechanisms to knit plain fabric, lace fabric, and non-run fabric with any number of barrier courses.

30 *Carrier and narrowing motion mechanism D*

This mechanism is of the usual construction consisting of a yarn carrier attachment 37, a narrowing attachment 38 and a feed control device 39, all of which are correlated to regulate 35 the distance of travel of the yarn carriers 40 for regulating the width of the fabric being knitted and for the periodic narrowing of the fabric by the transferring of knitted loops in a manner well known in the art. The feed control device 40 39 consists basically of the usual narrowing spindles 41 and 42 selectively operated by the pawl and ratchet connections 43 and 44 which are in turn manipulated by the arm 45 that is connected to a lever 46 carrying a roller 47 cooperatively associated with the narrowing cam 20 on 45 the main shaft. As this is the usual design as illustrated in the Reading Catalogue referred to, further detail description will be omitted. The narrowing attachment consists of the rear narrowing shaft 48 and front narrowing shaft 49 connected together by the arms 50. Connected to the shaft 49 is a link 51 pivotally connected to a lever 52 that carries a roller 53 cofunctioning with the main point cam 15 so that the shaft 49 may be dipped towards and away from the 50 row of needles of the knitting machine in the usual manner.

Needle mechanism E

60 The needle mechanism E is constructed along the usual lines of a Reading machine and consists of the row of needles 54 carried on a needle bar 55 which is given its vertical movements by the lever 56 carrying a roller 57 cooperating with 65 the needle cam 17. As this mechanism is of the usual construction, it is thought unnecessary to describe the same in detail or the remaining parts cofunctioning with the lever 56 to give the required vertical and rocking motions to each row 70 of needles 54.

Sinker and divider mechanism F

This mechanism is also of the usual type characteristic of a Reading full fashion knitting machine and consists basically of the sinkers 58,

dividers 59 and actuating mechanism designated in its entirety by the numeral 60.

Point mechanism G

I will now describe the most important part of my invention which may be completely manufactured and sold as a unitary article in the form of an attachment or may be incorporated in a complete knitting machine in the original construction thereof. The design of my invention 10 is such that when arranged in conjunction with other mechanism, it produces a new combination of mechanisms for accomplishing new results but may be utilized as an attachment to an old machine for accomplishing specific results well 15 known in the art. My improved point mechanism consists basically of a main point device 61, an auxiliary point device 62 and an actuating mechanism 63 therefor.

The main point device 61 consists of a main 20 row of points 64 carried on a bar 65 that in turn is fixed to a main point shaft 66 directly supported by the front narrowing shaft 49 of the narrowing mechanism. The shaft 66 is capable of longitudinal movements relative to the narrowing mechanism so that the relation of the points 64 with the row of needles 54 may be changed for a purpose hereinafter described.

The auxiliary point device 62 is in the form of an auxiliary row of points 67 carried by a bar 68. 30 This bar 68 is supported by brackets 69 that in turn are fixed to an auxiliary point shaft 70. This point shaft 70 is capable of longitudinal sliding movements and rotatable movements by being loosely mounted in brackets 71 that are 35 fixed to a manipulating shaft 72 that in turn has connected thereto a crank arm 73 connected to a link 74 that forms a connection with a bell crank lever 75 on the rear narrowing shaft 48. The bell crank lever 75 is connected by a link 76 40 with a cam device 77 in the form of a pivotal lever 78 having a roller 79 coacting with the auxiliary point cam 16.

For the purpose of controlling the turning action of the shaft 70 I provide a coil spring 80 45 utilizing its resiliency to normally force the points 67 towards the points 64. The shaft 66 carries a cam element 81 positioned to have a cam connection with a lug 82 fixed to the shaft 70 so that when lug 82 moves into a siding cam action 50 with element 81 the points 67 will be moved away from points 64 for accomplishment of objectives hereinafter set forth. A coil spring 83 is provided for each shaft and this coil spring has one end fixed to a projection 84 on the narrowing frame and its other end connected to one arm 85 of a centrally pivoted lever 86, the other arm 87 of which engages a collar 88 on its associated point shaft to constantly urge the shaft to the left. In other words, the lever 86 acts in opposition to the action of the cam block 28. The left end portions of both shafts or point rods 66 and 70 are provided with followers 89 that have a sliding contact with the cam device 34. Due to the fact that shafts 66 and 70 must be periodically moved as a unit and periodically moved independent of each other, the cam device 34 is constructed of the two members 33 and 35 hereinbefore set forth. The member 35 has a plain vertical surface 90 whereas member 33 70 has a cam or wedge surface 91 with the result that when the member 35 is moved horizontally by the cam block 28 both shafts 66 and 70 will be shifted longitudinally as a unit, 75

but upon member 33 being slid vertically independently of member 35 into an active position by the link 32, shaft 66 will be shifted independently of shaft 70 for bringing about a relative longitudinal displacement of the points 64 and 67.

Operation

Referring to Figs. 19 to 26, I have illustrated a single needle 92 of the row of needles, a single main point 93 of the row of points and a single auxiliary point 94 of the row of auxiliary points.

In Fig. 19 the points are about to start their downward travel whereas in Fig. 20 the point 93 has engaged the beard of the needle and the point 94 is moving into proper relation with the point 93.

In Fig. 21 the point 93 has engaged the last loop 95 of the fabric 96, the needle 92 continuing its downward movement so as to free itself of the loop 95 which is to be spread.

In Fig. 22 the needle 92 has passed downwardly below the knock over bits 97, the fabric 96 being retained upon the bits 97 with the loop 95 in engagement with the points 93. In this particular position it will be noted that the point 94 has moved into flat engagement with the point 93 and within the groove 98 of point 93.

In Fig. 23 the point 94 is moved slightly away from the point 93 so as to clear its groove and in Fig. 24 the point 93 has been shifted laterally relative to the point 94, the sinkers being retracted in this particular view to prevent interference between the point and the sinkers and dividers in the lateral shifting of the point.

In Fig. 25 the points have been lowered to engage with the required needles in the rising thereof to place the loop 95 that has now been spread by the separated points in position to engage around two needles in the raising of the row of needles. In Fig. 26 the points have been raised to their uppermost position and the needle 92 is now in position to receive a new thread for the forming of a new row of loops.

In Fig. 27 I have illustrated a horizontal sectional view of point 93 in its engagement with the needle 92.

In Fig. 28 I have illustrated a sectional view through the two points in their cooperative arrangement as shown in Fig. 22.

In Fig. 29 I have shown the points shifted relative to each other for the spreading of the loops, the position of the points corresponding to Fig. 24.

In Figs. 12, 13 and 15 I have designated by the numerals 19b to 26b, the various cam portions of the cams that are utilized to produce the relative position of the points and needles as shown in Figs. 19 to 26 inclusive.

In Figs. 16, 17 and 18, I have designated by the numerals 19b to 26b the various positions of the needles and points corresponding to the positions illustrated in Figs. 19 to 26 inclusive.

In the complete cycle of operation of the knitting machine, the power shaft 13 is set into operation for the usual actuation of the needle mechanism for producing any required number of plain courses and at a predetermined point in the formation of the fabric the loops for an interlocking or barrier course are formed by the action of the pattern motion mechanism. When this has been accomplished, the point mechanism in conjunction with the narrowing mechanism dips towards the row of needles with the result that the companion sets of points engaged with predetermined selective loops on predetermined needles to remove the same completely and bodily

from the needles. These predetermined selective loops as individually removed from their selective needles engage around the companion points 93 and 94 with the result that when the companion points are shifted laterally relative to each other such as by shifting the points 93 while holding the points 94 stationary, the selective loops will each be spread and while in this spread condition the points are then brought into operative relation with a pair of needles with the result that the spread loop is passed over a pair of companion needles. I wish to call attention to the fact that the spreading of the loops takes place independently of the movement of the needles, that is to say, each loop is removed bodily from its creating needles and then spread independently by the action of the companion points thereby relieving the needles of any strains or distortion effects and enabling the spreading of the loop in a more practical and effective manner.

In the accomplishment of the dipping of the points and their relative displacement, the pattern mechanism through its various instrumentalities functions to time the vertical movement of the cam block 28 for shifting shafts 66 and 70 as a unit for placing the points in the proper alignment with predetermined needles in predetermined wales. After this has been accomplished the narrowing mechanism is set into operation through cam 15 for dipping the narrowing mechanism and with it the point mechanism. The points will then engage predetermined loops and in the downward movement of the needles remove such loops from their needles. After this has been accomplished, cam member 33 is slid relative to member 35 so as to bring the cam surface 91 of member 33 into proper engagement with the follower of shaft 66 for shifting shaft 66 longitudinally independently of shaft 70. This action causes the shifting of points 93 relative to points 94 for spreading the loops.

Upon the upward movement of the needles, these spread loops are transferred to the needles by the action of the narrowing mechanism. As a final step in the cycle of operation, the cam block 28 is moved an increased elevation by the point motion mechanism for giving a second shifting motion to the pair of shafts 66 and 70 as a unit for placing the points into relation with a different group of needles corresponding to another group of wales in the fabric, the points thereafter functioning to spread the new loops in the new wales thereby enabling the positioning of spread loops in staggered relation in the various barrier or interlocking courses. In other words, shafts 66 and 70 have two successive movements as a unit, either to the right or to the left through the action of the cam block 28, but the companion shafts 66 and 70 only have one relative movement to each other for the spreading of the loops through the action of the cam member 33.

In the swinging movement of points 67 towards points 64 by the crank arm 73 and the manipulating parts therefor, the lug 82 will eventually engage the cam element 81 so as to accomplish a slight lateral displacement of the points 64 and 67 as clearly shown in Fig. 24 to allow an independent lateral shifting of the point 64 (93 in Fig. 24) in the spreading of the loop. Due to the formation of the groove in points 64 and the contour of the points 67, I accomplish a centering action between the points 64 and 67 to assure their proper alignment and the proper positioning within predetermined selective loops that are to be spread. In the shifting of the shaft 13 by

the shifting device 14 for narrowing operations, the actuation of the shifting device 14 is controlled by the pattern motion mechanism which also controls the sliding movement of the cam block 28 and cam member 35 for accomplishing the desired movements of the shafts 66 and 70, collectively or individually. Due to the use of the spring 80 the points 67 are yieldably urged towards points 64 but this spring 80 will yield in the engagement of lug 82 with cam element 81 for allowing slight turning of the shaft 70 for moving the points 67. In the use of my machine the pattern motion mechanism may be designed along customary lines to repeat predetermined operations of the machine as often as possible, that is to say, the machine may be operated for a number of times to provide the necessary plain courses for producing plain fabric and then the pattern motion mechanism operated to manipulate the machine to produce any number of interlocking courses and further the pattern motion mechanism may operate in the usual manner to produce ordinary lace or net fabric, these actions depending entirely upon the setting of buttons on the pattern chain of the pattern motion mechanism. It can be very easily understood that by providing the usual buttons in proper positions on the pattern chain, every course, or every other course, or every third course may be made a barrier course thereby producing a fabric having run proof properties or the buttons may be so positioned as to only provide a relatively few barrier courses in a restricted portion of the fabric such as directly below the welt of the stocking as shown in the drawing.

Simplified semi-automatic point attachment

In Figs. 33 to 37 I have shown a simplified form of attachment which is semi-automatic in operation and which may be in a very simple manner applied to commonly known full fashion knitting machines for cooperation with the groups of mechanisms for producing one or more barrier courses in a particular portion of a stocking such as directly below the welt for preventing garter runs or producing barrier courses over the entire area of the stocking to prevent runs in any portion of the stocking.

In Figs. 33 to 37, which shows one embodiment of my invention, it will be noted that the attachment consists basically of companion point devices 100 and 101, the device 100 consists of a main row of points 102, on a bar 103 whereas the other device consists of an auxiliary row of points 104 mounted on a bar 105. These rows of points are adapted to be adjusted together or relatively on a single point shaft 106, whereas in the completely automatic machine heretofore described, I have illustrated two point shafts.

The brackets 107 supporting the bar 103 are fixedly mounted on the shaft 106 whereas the brackets 108 of bar 105 are slidably mounted on the shaft 106, a coil spring 109 being arranged in engagement with one of the brackets 108 and a collar 110 fixed to shaft 106 to accommodate joint movements of the brackets 107 and 108 and further allow brackets 108 to be given a movement independent of brackets 107 to take care of the two positionings of the point devices for accommodating the staggered relation of spread loops in the various wales of the fabric and to accommodate relative movements of the point devices in the spreading of the loops.

One of the brackets 108 is provided with a cam

surface 111 coacting with an adjustable contact screw 112 carried by a finger piece 113 swingingly mounted on shaft 106. It will be noted that the spring normally holds the slidably mounted bracket 108 in contact with the screw 112 and through this connection, finger piece 113 is in close contact with bracket 107. Thus, it will be appreciated that shifting of the shaft 106 to the left moves bracket 107, finger piece 113 and bracket 108 as a unit, but upon turning of the finger piece 113, the screw 112 will engage the cam surface 111 to move the bracket 108 independently against the resiliency of the spring 109 so as to shift point device 101 independent of point device 100 for spreading the loops carried by the rows of points. There are two ways in which the shaft 106 may be given two separate and distinct progressive movements to the left, one a manually operated device designated broadly by the numeral 114 and the other by an automatic device designated by the numeral 115, either one of which may be used independently of the other. The manually operated device consists of a cam collar 116 fixed to the shaft 106 and having its cam surface 117 flatly contacted with the cam surface 118 of the cam head 119 of the handle 120 for holding the shaft 106 in its first position. With this arrangement it will be appreciated that with the parts set as shown in Fig. 34, the rows of points carried by the shaft 106 will engage with loops of predetermined wales in the dipping of the narrowing mechanism but upon turning of the handle 120 the shaft 106 will be shifted to the left which is its second position for placing the row of points into engagement with predetermined loops in an adjacent group of wales thereby accomplishing the staggering relation of the spread loops in succeeding courses. The cam head 119 is slidably mounted on the shaft 106 in abutting relation with a collar 121 which is also slidably mounted on shaft 106, the collar being continuously biased into engagement with the cam head by means of a contractile spring 130 anchored at one end to bracket member 131, and fastened at its other end to a pin 132 secured to the collar 121. The pin 132 passes through and is slidable in slot 133 of a plate 134 secured to the bracket arm 50 of the narrowing mechanism, thus permitting the collar 121 to move axially with the shaft 106 when the latter is shifted horizontally by the automatic device 115. A bushing 136 is adjustably secured to the collar 121 by a threaded portion 136a screwed into one end of the collar, Fig. 34, and is locked in its adjusted position by lock-nut 135.

In the construction of the automatic device 115 I provide a cam block 122 having a cam surface 123 that coacts with a follower 124 adjustably secured in the end of bushing 136 by a set screw 137, to normally hold the shaft 106 in its first position and to shift the shaft horizontally to its second position thereby changing the relative positions of the points in relation to predetermined wales of the fabric for accomplishing staggered relation of the spread loops. As shown in Fig. 34, sufficient clearance is provided between the end of shaft 106 and follower 124 to permit longitudinal adjustment of these members. The cam block 122 is operated by a link 138 having a pivotal connection with a lever 125 that carries a roller 126 adapted to be selectively engaged with cams 127 and 128 mounted on the cam shaft, one of the cams to hold the block in its normal position as illustrated in Fig. 33 and the other to increase the elevation of the cam block to accom-

plish a longitudinal shifting of the shaft 106 in a manner well known in the art and characteristic of lace attachments for full fashion knitting machines.

- 5 I am aware of the fact that lace attachments have been used before for giving variable sliding movements to the point shaft of lace mechanism and therefore I do not consider the details of construction of the particular automatic device 115, 10 illustrated as a part of my invention, my basic invention residing in the novel arrangement and combination of parts whereby loops in staggered position in succeeding courses may be spread to pass around companion needles.
- 15 In the operation of the semi-automatic point attachment, the knitting machine is operated in the usual manner to produce row after row of plain loops and at designated periods depending upon the action of the usual lace attachment or 20 narrowing attachment, the narrowing mechanism is caused to dip to first bring the main row of points 102 into engagement with predetermined loops in predetermined wales and thereafter the auxiliary row of points 104. When this has been 25 accomplished the finger piece 113 is manipulated for changing the position of the two rows of points for spreading the loops to enable the same to engage around companion needles in the rising of the needles of the knitting machine. Following this action the narrowing mechanism rises 30 to repeat its dipping operation but just before this takes place the handle 120 is manipulated manually or the automatic device 115 is set into operation for giving a longitudinal movement to 35 shaft 106 which places the various points in co-operative arrangement with a new set of loops in a new group of wales of the fabric so that when the rows of points perform their spreading operations they will accomplish spreading of the loops 40 in different positions in the new course as compared with the old course so as to accomplish a staggered relation of the spread loops throughout the area of the fabric. When the automatic mechanism 115 is to be operated the cam shaft is 45 shifted to bring the cam 128 into engagement with the roller 126 for elevating the cam block 122 to cause the shifting of the shaft 106 thereby regulating the particular loops in the particular wales engaged by the row of points.
- 50 My semi-automatic point attachment is particularly adapted for providing "run" barriers in a restricted portion of a stocking and will have a particular use in the industry where an inexpensive simplified attachment is desired. It will also 55 be noted that the basic principles of operation of the semi-automatic attachment are identical with the basic principles of operation of the completely automatic machine in that selected loops are spread and arranged in staggered relation in succeeding courses and this spreading, skipping and 60 alternating the position of the spread loops may be carried out in any number of courses by the manipulation of the ordinary lace attachment commonly used on hosiery knitting machines.
- 65 In concluding I wish to state that various combinations of relative positions may be established between the row of needles and the rows of points for accomplishing the spreading of loops in various directions to produce slightly modified effects 70 in the finished fabric. For instance, I have shown in Figs. 38, 39 and 40 diagrammatically three relative positions of the points and needles.

In Fig. 38 I have shown associated pairs of points of the rows of points each arranged in 75 close relation with alternate needles 92 for joint

engagement with the loop on the associated needle, whereas in Fig. 39 I have shown the points 94 spread from the points 93 with each point 93 aligning with alternate needles and points 94 aligning with adjacent needles for depositing loops around pairs of needles. 5

In Fig. 40 I have illustrated point 94 moved a two needle distance so that the spread loop may be passed around three needles. I wish to call attention to the fact that the point 94 may be 10 spread any required distance in relation to point 93 depending upon the specific effect to be accomplished in the finished fabric.

The improvements herein specifically shown and described, by which the above results are 15 obtained, can be changed and modified in various ways without departing from the invention herein disclosed and hereinafter claimed.

What is claimed is:

1. The combination of a series of needles disposed in a predetermined plane, a pair of points adjacently disposed above the needles and adapted to enter a loop formed around one of the needles, means for moving said points longitudinally relative to the needles to effect entrance of 25 one of said points into the loop between the loop and the needle occupied thereby, means for relatively moving the needle and said one of the points laterally away from each other, means for moving the second of said points longitudinally of and 30 relative to the first said point to effect entrance of said second point into said loop, said means operating in the order named and means for relatively shifting the points laterally within the loop to spread the loop across a plurality of the needles. 35

2. The combination of a series of needles disposed in a predetermined plane, a pair of points adjacently disposed above the needles and adapted to enter a loop formed around one of the needles, means for moving said points longitudinally 40 relative to the needles to effect entrance of one of said points into the loop between the loop and the needle occupied thereby, means for relatively moving the needle and said one of the points laterally away from each other, means for moving 45 the second of said points longitudinally of and relative to the first said point to effect entrance of said second point into said loop, said means operating in the order named, means for relatively moving the points to separate said points within 50 the loop, and means for relatively shifting the separated points laterally within the loop to spread the loop across a plurality of the needles.

3. The combination of a series of needles disposed in a predetermined plane, a pair of points 55 adjacently disposed above the needles and adapted to enter a loop formed around one of the needles, means for moving said points longitudinally relative to needles to effect entrance of one of said points into the loop between the loop and 60 the needle occupied thereby, means for effecting relative lateral and longitudinal movement between the needles and said entered point to effect withdrawal of the occupied needle from the loop, means for moving the second of said points longitudinally of and relative to the first said point to 65 effect entrance of said second point into said loop, said means operating in the order named, means for relatively moving the points to separate said points within the loop, and means for relatively 70 shifting the separated points laterally within the loop to spread the loop across a plurality of the needles.

4. The combination of a series of needles disposed in a predetermined plane, a pair of points 75

- adjacently disposed above the needles and adapted to enter a loop formed around one of the needles, means for moving said points longitudinally relative to the needles to effect entrance of one of said points into the loop between the loop and the needle occupied thereby, means for effecting relative lateral and longitudinal movement between the needles and said entered point to effect withdrawal of the occupied needle from the loop, means for moving the second of said points longitudinally of and relative to the first said point to effect entrance of said second point into said loop, said means operating in the order named, means for relatively moving the points to separate said points within the loop, means for relatively shifting the separated points laterally within the loop to spread the loop across a plurality of the needles, means for effecting relative longitudinal movement between the laterally shifted points and the needles to effect entrance of the needles covered by the spread loop into said spread loop, and means for withdrawing the points from the spread loop leaving said spread loop disposed around said plurality of needles.
5. The combination of a series of needles disposed in a predetermined plane, a pair of points adjacently disposed above the needles and adapted to enter a loop formed around one of the needles, means for moving said points longitudinally relative to the needles to effect entrance of one of said points into the loop between the loop and the needle occupied thereby, means for effecting relative lateral and longitudinal movement between the needles and said entered point to effect withdrawal of the occupied needle from the loop, means for moving the second of said points longitudinally of and relative to the first said point to effect entrance of said second point into said loop, said means operating in the order named, means for relatively moving the points to separate said points within the loop, means for relatively shifting the separated points laterally within the loop to spread the loop across a plurality of the needles, means for effecting relative longitudinal movement between the laterally shifted points and the needles to effect entrance of the needles covered by the spread loop into said spread loop leaving said spread loop disposed around said plurality of needles, and means for returning said laterally shifted points to their position above the needles.
6. The combination of a series of needles disposed in a predetermined plane, a pair of points adjacently disposed above the needles and adapted to enter a loop formed around one of the needles, means for moving said points longitudinally relative to the needles to effect entrance of one of said points into the loop between the loop and the needle occupied thereby, means for effecting relative lateral and longitudinal movement between the needles and said entered point to effect withdrawal of the occupied needle from the loop, means for moving the second of said points longitudinally of and relative to the first said point to effect entrance of said second point into said loop, said means operating in the order named, means for relatively moving the points to separate said points within the loop, means for relatively shifting the separated points laterally within the loop to spread the loop across a plurality of the needles, means for effecting relative longitudinal movement between the laterally shifted points and the needles to effect entrance of the needles covered by the spread loop into said spread loop into
- said loop, means for withdrawing the points from the spread loop leaving said spread loop disposed around said plurality of needles, means for returning said laterally shifted points to their position above the needles, and means for shifting said points laterally as a unit into alignment with another of the needles of said series.
7. The combination of a series of needles disposed in a predetermined plane, a series of points disposed in a plane substantially parallel to that of the needles, a second series of points respectively paired and aligned with corresponding points of the first point series in common planes substantially perpendicular to the plane of the needle series, means for aligning the point pairs respectively with predetermined needles of the needle series, means for effecting relative longitudinal movement between the points and the needles to effect entrance of one series of points into loops disposed respectively on said predetermined needles, means for relatively moving the needles and said one series of points laterally away from each other prior to entrance of the second series of points into said loops, means for effecting relative longitudinal movement between the paired points of said two series of points to effect entrance of the second series of points into said loops respectively, and means for effecting lateral relative movement between the two series of points to spread each entered loop over a plurality of the needles of the needle series.
8. The combination of a series of needles disposed in a predetermined plane, a series of points disposed in a plane substantially parallel to that of the needles, a second series of points respectively paired and aligned with corresponding points of the first point series in common planes substantially perpendicular to the plane of the needle series, means for aligning the point pairs respectively with predetermined needles of the needle series, means for effecting relative longitudinal movement between the points and the needles to effect entrance of one series of points into loops disposed respectively on said predetermined needles, means for effecting relative movement between the needles and the points in said perpendicular planes to release the loops from the needles, means for effecting relative longitudinal movement between the paired points of the two series of points to effect entrance of the second series of points into said loops respectively between the needles and the points holding the loops, and means for effecting lateral relative movement between the two series of points to spread each entered loop over a plurality of the needles of the needle series.
9. The combination of a series of needles disposed in a predetermined plane, a series of points disposed in a plane substantially parallel to that of the needles, a second series of points respectively paired and aligned with corresponding points of the first point series in common planes substantially perpendicular to the plane of the needle series, means for aligning the point pairs respectively with predetermined needles of the needle series, mechanism for effecting relative longitudinal movement between the points and the needles to effect entrance of one series of points into loops disposed respectively on said predetermined needles, said mechanism effecting relative transverse movement between the needles and the points in said perpendicular planes prior to entrance of the second series of points into said loops, means for effecting relative longitudinal movement between the paired points of the two

series of points to effect entrance of the second series of points into said loops respectively between the needles and the points holding the loops, said mechanism effecting relative longitudinal movement between the needles and the points to withdraw the needles from the loops suspended by the points, and means for effecting lateral relative movement between the two series of points to spread each entered loop over a plurality of the needles of the needle series.

10. The combination of a series of needles disposed in a predetermined plane, a series of points disposed in a plane substantially parallel to that of the needles, a second series of points respectively paired and aligned with corresponding points of the first point series in common planes substantially perpendicular to the plane of the needle series, means for aligning the point pairs respectively with predetermined needles of the 15 needle series, mechanism for effecting relative longitudinal movement between the points and the needles to effect entrance of one series of points into loops disposed respectively on said predetermined needles, means for effecting relative transverse movement between the needles and the points in said perpendicular planes, prior to entrance of the second series of points into said loops, means for effecting relative longitudinal movement between the paired points of the two 20 series of points to effect entrance of the second series of points into said loops respectively between the needles and the points holding the loops, said mechanism effecting relative longitudinal movement between the needles and the 25 points to withdraw the needles from the loops suspended by the points, and means for effecting lateral relative movement between the two series of points to spread each entered loop over a plurality of the needles of the series, said mechanism effecting relative longitudinal movement between the needles and points to effect entrance of said needle pluralities into the spread loops respectively.

11. The combination of a series of needles disposed in a predetermined plane, a series of points disposed in a plane substantially parallel to that of the needles, a second series of points respectively paired and aligned with corresponding points of the first point series in common planes substantially perpendicular to the plane of the needle series, means for aligning the point pairs respectively with predetermined needles of the needle series, mechanism for effecting relative longitudinal movement between the points and the needles to effect entrance of one series of points into loops disposed respectively on said predetermined needles, said mechanism effecting relative transverse movement between the needles and the points in said perpendicular planes prior to entrance of the second series of points into said loops, means for effecting relative longitudinal movement between the paired points of the two series of points to effect entrance of the second series of points into said loops respectively between the needles and the points holding the loops, said mechanism effecting relative longitudinal movement between the needles and the points to withdraw the needles from the loops suspended by the points, means for effecting lateral relative movement between the two series of points to spread each entered loop over a plurality of the needles of the series, said mechanism effecting relative longitudinal movement between the needles and points to effect entrance of said needle pluralities respectively into the spread loops.

loops and to effect withdrawal of the laterally separated points of each pair from the spread loops, and means for effecting lateral movement between the point series to realign the points of the respective pairs in said perpendicular planes respectively.

12. The combination of a series of needles disposed in a predetermined plane, a series of points disposed in a plane substantially parallel to that of the needles, a second series of points respectively paired and aligned with the first point series in common planes substantially perpendicular to the plane of the needle series, means for aligning the point pairs respectively with predetermined needles of the needle series, mechanism for effecting relative longitudinal movement between the points and the needles to effect entrance of one series of points into loops disposed respectively on said predetermined needles, said mechanism effecting relative transverse movement between the needles and the points in said perpendicular planes prior to entrance of the second series of points into said loops, means for effecting relative longitudinal movement between the paired points of the two series of points to effect entrance of the second series of points into said loops respectively between the needles and the points holding the loops, said mechanism effecting relative longitudinal movement between the needles and the points to withdraw the needles from the loops suspended by the points, means for effecting lateral relative movement between the two series of points to spread each entered loop over a plurality of the needles of the series, said mechanism effecting relative longitudinal movement between the needles and points to effect entrance of said needle pluralities respectively into the spread loops and to effect withdrawal of the laterally separated points of each pair from the spread loops, means for effecting lateral movement between the point series to realign the points of the respective pairs in said perpendicular planes respectively, and means for moving the two point series as a unit parallel to and longitudinally of the plane of the needle series to align the respective point pairs with other needles of the needle series respectively.

13. In a straight knitting machine, the combination of a series of spring beard needles having point-receiving grooves therein and two sets of companion points cooperatively associated with said needles, means for forming a course composed of alternate sinker and needle loops with needles in said needle loops, means for relatively moving said needles and points to cause one set of points to enter the grooves of predetermined needles and engage the needle loops thereon, means for relatively moving the last named set of points and said needles to remove the loops from the needles, means for causing the second set of points to descend into the needle loops engaged by the first set of points, means for laterally shifting one of said sets of points and the bight portions of the needle loops carried thereby into position to be engaged by other needles in adjacent wales of the fabric, and means for delivering said spread loops onto the needles comprising means for vertically moving the needles and points relative to each other.

14. In a straight knitting machine, the combination of a series of spring beard needles having point-receiving grooves therein and two sets of companion points cooperatively associated with said needles, means for forming a course composed of alternate sinker and needle loops with

needles in said needle loops, means for relatively moving said needles and points to cause one set of points to enter the grooves of predetermined needles and engage the needle loops thereon,
 5 means for relatively moving the last named set of points and said needles to remove the loops from the needles, means for causing the second set of points to descend into the needle loops engaged by the first set of points, means for laterally shifting the first named set of points and the bight portions of the needle loops carried thereby into position to be engaged by other needles in adjacent wales of the fabric, and means for delivering said spread loops onto the needles
 10 comprising means for vertically moving the needles and points relative to each other.

15. In a straight knitting machine, the combination of a series of spring beard needles having point-receiving grooves therein and two sets 20 of companion points cooperatively associated with said needles, means for forming a course composed of alternate sinker and needle loops with needles in said needle loops, means for vertically moving one of said sets of points relative to the other to cause said sets to successively descend into selected needle loops and including means for transversely relatively moving said needles and points prior to the entrance of the second of said sets into said selected needle loops, means for laterally shifting one of said sets of points and the bight portions of the needle loops carried thereby into position to be engaged by other needles in adjacent wales of the fabric, and means for delivering said spread loops onto the needles
 25 comprising means for vertically moving the needles and points relative to each other.

16. A full fashioned knitting machine comprising, in combination, a series of spring beard needles having point-receiving grooves therein and two sets of companion points cooperatively associated with said needles, means for forming a course composed of alternate sinker and needle loops with needles in said needle loops, means for relatively moving said needles and points to cause one set of points to enter the grooves of alternate needles in the row of needles and engage the needle loops thereon, means for relatively moving the last named set of points and said needles to remove the loops from the needles, means for causing the second set of points to descend into the needle loops engaged by the first set of points, means for laterally shifting one of said sets of points and the bight portions of the needle loops carried thereby into position to be engaged by other needles in adjacent wales of the fabric, and means for delivering said spread loops onto the needles comprising means for causing the needles to rise relative to said points.
 50

17. The combination of a series of needles disposed in a predetermined plane, a series of points disposed in a plane substantially parallel to that of the needle series, a second series of points respectively paired and aligned with the points of the first series in planes substantially perpendicular to the plane of the needle series, a rod supporting the first series of points, a rod supporting the second series of points, a head operable in a plane transverse to the axes of said rods, means for resiliently pressing said rods into contact with said head, means for moving said head and said rods as a unit longitudinally of the needle series to align the respective point pairs with predetermined needles of the needle series, and a cam operating between said head
 55

and one of said rods for moving said rod relative to the other of said rods for effecting relative lateral movement between the points of each point pair in a direction longitudinally of the needle series.
 5

18. The combination of a series of needles disposed in a predetermined plane, a series of points disposed in a plane substantially parallel to that of the needle series, a second series of points respectively paired and aligned with the points of the first series in planes substantially perpendicular to the plane of the needle series, a rod supporting the first series of points, a rod supporting the second series of points, means for resiliently turning one of said rods relative to the other of said rods to effect firm contact between the points of each pair, and means for positively turning the resiliently turned rod in an opposite direction to separate the points of each pair in the perpendicular plane occupied thereby.
 20

19. The combination of a series of needles disposed in a predetermined plane, a series of points disposed in a plane substantially parallel to that of the needle series, a second series of points respectively paired and aligned with the points of the first series in planes substantially perpendicular to the plane of the needle series, a rod supporting the first series of points, a rod supporting the second series of points, a head operable in a plane transverse to the axes of said rods, means for resiliently pressing said rods into contact with said head, means for moving said head and said rods as a unit longitudinally of the needle series to align the respective point pairs with predetermined needles of the needle series, means for resiliently turning one of said rods relative to the other of said rods to effect firm contact between the points of each pair, means for positively turning the resiliently turned rod in an opposite direction to separate the points of each pair in the perpendicular plane occupied thereby, and a cam operating between said head and one of said rods for moving said rod relative to the other of said rods for effecting relative lateral movement between the points of each point pair in a direction longitudinally of the needle series.
 25

20. The combination of a series of needles disposed in a predetermined plane, a main series of points disposed in a plane substantially parallel to that of the needle series, an auxiliary series of points respectively paired and aligned with the points of the main series in planes substantially perpendicular to the plane of the needle series, a dip shaft substantially parallel to the plane of the needle series, a rod carried by the dip shaft and supporting the main series of points, an operating shaft parallel to and carried by the dip shaft, brackets on the operating shaft, a second rod supporting the auxiliary point series and rotatably mounted in the brackets on the operating shaft, means for resiliently turning the auxiliary point rod in one direction in said brackets to press the auxiliary points firmly into contact with the main points respectively, means for turning the operating shaft to effect longitudinal movement of the auxiliary points relative to the main points, and means for turning the auxiliary point rod in an opposite direction to separate the auxiliary points from the main points in said perpendicular planes respectively.
 50

21. The combination of a series of needles disposed in a predetermined plane, a main series of points disposed in a plane substantially parallel
 55

70

75

to that of the needle series, an auxiliary series of points respectively paired and aligned with the points of the main series in planes substantially perpendicular to the plane of the needle series, 5 a dip shaft substantially parallel to the plane of the needle series, a rod carried by the dip shaft and supporting the main series of points, an operating shaft parallel to and carried by the dip shaft, brackets on the operating shaft, 10 a second rod supporting the auxiliary point series and rotatably mounted in the brackets on the operating shaft, means for resiliently turning the auxiliary point rod in one direction in said brackets to press the auxiliary points firmly into contact with the main points respectively, means 15 for turning the operating shaft to effect longitudinal movement of the auxiliary points relative to the main points, means for turning the auxiliary point rod in an opposite direction to separate the auxiliary points from the main points in said perpendicular planes respectively, and means for shifting the main point rod axially and longitudinally of the auxiliary point rod to shift the main points relative to the auxiliary 20 points in a direction longitudinally of the plane 25 of the needle series.

22. The combination of a series of needles disposed in a predetermined plane, a main series of points disposed in a plane substantially 30 parallel to that of the needle series, an auxiliary series of points respectively paired and aligned with the points of the main series in planes substantially perpendicular to the plane of the needle series, a dip shaft substantially parallel to the 35 plane of the needle series, a rod carried by the dip shaft and supporting the main series of points, an operating shaft parallel to and carried by the dip shaft, brackets on the operating shaft, a second rod supporting the auxiliary point 40 series and rotatably mounted in the brackets on the operating shaft, means for resiliently turning the auxiliary point rod in one direction in said brackets to press the auxiliary points firmly into contact with the main points respectively, a 45 head transversely disposed to said rods, means for resiliently pressing said rods axially into contact with said head, means for moving the head and rods as a unit to align the point pairs with predetermined needles of the needle series, means 50 for moving the dip shaft laterally to effect engagement of the main points with the aligned needles, means for turning the operating shaft to effect longitudinal movement of the auxiliary points relative to the main points, means for 55 turning the auxiliary point rod in an opposite direction to separate the auxiliary points from the main points in said perpendicular planes respectively, and a cam operating between the head and the main point rod to shift the main points laterally from the auxiliary points in a direction longitudinally of the plane of the needle series.

23. In the art of knitting one or more barrier courses in a fabric on a straight knitting machine having a series of spring beard needles with point 60 receiving grooves therein and two sets of companion points cooperatively associated with said needles, the method which comprises forming loops in a course composed of alternate sinker and needle loops with needles in said needle loops, relatively moving said needles and points to cause one set of points to enter the grooves of the needles and inserting the points into selected needle loops, relatively moving the last named set of points and said needles to remove the loops 65 from the needles, causing the second set of points

to descend into the needle loops engaged by the first set of points, laterally shifting one of said sets of points and the bight portions of the needle loops carried thereby into position to be engaged by other needles in adjacent wales of the fabric, 5 and delivering said spread loops onto the needles by vertically moving the needles and points relative to each other.

24. In the art of knitting fabric on a straight knitting machine having a series of spring beard 10 needles with point-receiving grooves therein and two sets of companion points cooperatively associated with said needles, the method which comprises forming loops in a course composed of alternate sinker and needle loops with needles in 15 said needle loops, relatively moving said needles and points to cause one set of points to enter the grooves of the needles and inserting the points into selected needle loops, relatively moving the last named set of points and said needles to remove the loops from the needles, causing the second set of points to descend into the needle loops engaged by the first set of points, laterally shifting the first named set of points and the bight 20 portions of the needle loops carried thereby into position to be engaged by other needles in adjacent wales of the fabric, and delivering said spread loops on the two sets of points onto the needles by vertically moving the needles and points relative to each other.

25. In the art of knitting a fabric on a straight knitting machine having a series of spring beard needles with point-receiving grooves therein and two sets of companion points cooperatively associated with said needles, the method which comprises forming loops in a course composed of alternate sinker and needle loops with needles in 30 said needle loops, vertically moving one of said sets of points relative to the other to cause said sets to successively descend into selected needle loops, transversely moving said needles and points prior to the entrance of the second of said sets into said selected needle loops, laterally shifting one of said sets of points and the bight portions 35 of the needle loops carried thereby into position to be engaged by other needles in adjacent wales of the fabric, and delivering said spread loops onto the needles by vertically moving the needles and points relative to each other.

26. In the art of knitting one or more barrier courses in a stocking blank on a full fashioned knitting machine having a series of spring beard needles with point-receiving grooves therein and two sets of companion points cooperatively associated with said needles, a method which comprises forming loops in a course composed of alternate sinker and needle loops with needles in 40 said needle loops, relatively moving said needles and points to cause one set of points to enter the grooves of alternate needles in the row of needles and inserting the points into needle loops, relatively moving the points and said needles to remove the loops from the needles, causing the second set of points to descend into the needle loops engaged by the first set of points, laterally shifting one of said sets of points and the bight 45 portions of the needle loops carried thereby into position to be engaged by other needles in adjacent wales of the fabric, and delivering said 50 spread loops onto the needles by causing the needles to rise relative to said points.

27. A straight knitting machine for automatically producing a non-run fabric comprising, in combination, a series of spring beard needles 55 having point receiving grooves therein; a first

series of points cooperatively associated with said needles and spaced to engage alternate needles in the series of needles, a rod supporting said first series of points; a second series of points 5 respectively paired and aligned with the points of the first series, a rod supporting the second series of points; means for forming a fabric course composed of alternate sinker and needle loops; means for relatively moving said needles 10 and points to cause said points to enter alternate needle loops; means operable prior to entry of said points into said needle loops for actuating both of said point rods in a longitudinal direction into position to cause the points to engage 15 selected needles in the row of needles; means operable after said needle loops are engaged by the points for longitudinally shifting one of said point rods and its points, and the bight portions of the needle loops carried thereby, a distance 20 of one needle into position to be engaged by other needles in adjacent wales of the fabric; means for delivering the bight portions of said loops onto said other needles comprising means for vertically moving the needles and points 25 relative to each other, thereby to produce an interlocking course; means for shifting the other of said point rods longitudinally to cause said points in the next succeeding interlocking course to descend into engagement with the loops on the 30 needles in said adjacent wales of the fabric, thereby to stagger said locking loops coursewise in succeeding interlocking courses and provide a plurality of locking loops in every wale of the fabric; and means including a plurality of pattern 35 controlled cam members respectively associated with the foregoing means for automatically and uninterruptedly operating said means in timed relation with each other, and in synchronism with the movements of said needles, in pre- 40 selected courses of the fabric during the knitting thereof.

28. A full fashioned knitting machine for automatically producing a non-run fabric comprising, in combination, a cam shaft axially shiftable 45 from its plain knitting position to a narrowing position; a series of spring beard needles having point receiving grooves therein; a narrowing machine arranged to dip toward said needles when the cam shaft is in the narrowing position; a 50 first series of points cooperatively associated with said needles and spaced to engage alternate needles in the series of needles, a rod supporting said first series of points and carried by said narrowing machine; a second series of points 55 respectively paired and aligned with the points of the first series, a rod supporting the second series of points and carried by said narrowing machine; means operative when the cam shaft is in its plain knitting position for forming a fabric course composed of alternate sinker and needle loops; means, operative when said course of loops has been formed, for shifting the cam shaft to its narrowing position; means including said narrowing machine, operative when the cam shaft 60 is in said narrowing position, for relatively moving said needles and points to cause said points to enter alternate needle loops; means operable prior to entry of said points into said needle loops for actuating both of said point rods in a longitudinal direction into position to cause the points to engage selected needles in the row of needles; means operable after said needle loops are engaged by the points for longitudinally shifting one of said point rods and its points, and the 65 bight portions of the needle loops carried there- 70

by, a distance of one needle into position to be engaged by other needles in adjacent wales of the fabric; means for delivering the bight portions of said loops onto said other needles comprising means including said narrowing machine for vertically moving the needles and points relative to each other, thereby to produce an interlocking course; means for shifting the other of said point rods longitudinally to cause said points in the next succeeding interlocking course 10 to descend into engagement with the loops on the needles in said adjacent wales of the fabric, thereby to stagger said locking loops coursewise in succeeding interlocking courses and provide a plurality of locking loops in every wale of the 15 fabric; and means including a plurality of pattern controlled cam members, operative when the cam shaft is in its narrowing position, respectively associated with the foregoing means for automatically and uninterruptedly operating said 20 means in timed relation with each other, and in synchronism with the movements of said needles, in preselected courses of the fabric during the knitting thereof.

29. A full fashioned stocking knitting machine 25 for automatically producing a non-run area in a stocking blank comprising, in combination, a series of spring beard needles having point receiving grooves therein; needle actuating mechanism; a narrowing machine arranged to dip toward said 30 needles; a first set of points carried by said narrowing machine and cooperatively associated with said needles and spaced to engage selected needles in the series of needles; a second series of points carried by said narrowing machine respectively 35 paired and alignable with the points of the first series; means including said needles for forming a fabric course composed of alternate sinker and needle loops; means, operative when said course of loops has been formed, for actuating the narrowing machine to move said points relative to the needles to cause said first set of points to enter selected needle loops; means carried by the narrowing machine for causing the second series of points to enter said needle loops; means operable 45 after said needle loops are engaged by said points for longitudinally shifting one of said series of points, and the bight portions of the needle loops carried thereby, to a position to be engaged by other needles in adjacent wales of the stocking blank; means for delivering the bight portions of said loops onto said other needles comprising means including the narrowing machine and the needle actuating mechanism for vertically moving the needles and points relative 50 to each other, thereby to produce an interlocking course; means for shifting at least one of said series of points longitudinally to cause the points in a succeeding interlocking course to descend into engagement with the loops on the 55 needles in said adjacent wales of the stocking blank to stagger said locking loops coursewise in succeeding interlocking courses; means for fashioning the stocking blank at predetermined places therein; and means including a plurality of pattern controlled cam members respectively associated with the foregoing means for automatically and uninterruptedly operating said means in timed relation with each other, and in synchronism with the movements of said needles, in pre- 60 selected courses of the stocking blank during the knitting thereof.

30. A knitting mechanism comprising a bank of needles, a set of point units each including a pair of relatively movable points, mechanism for 65 70 75

effecting longitudinal movement between the units and the needles to insert one set of the points of the units into loops on the needles and for relatively moving the units and the needles transversely prior to entrance of the second set of points of the units into said loops, means for moving the sets relatively to effect said entrance, said mechanism being operative to withdraw the needles from the loops, and means for effecting lateral movement between said sets.

31. In a flat knitting machine for producing non-run hosiery, the combination with a series of needles and their cooperating knitting elements, of a point bar having a series of points spaced to engage with each alternate needle of the needle series, a second point bar having a series of points similarly spaced to engage with each alternate needle of the needle series, means for moving said

point bars toward and away from the needle series longitudinally of the needle shanks to engage said points with the needle eyes and pattern mechanism for controlling the operation of each of said point bars in designated courses to register the points of both of said bars with each other and with identical alternate needles, and thereafter to move one of said bars lengthwise of the needle series to displace a portion of each of the loops on said alternate needles over an adjacent needle, 10 and on designated intermediate courses to register the points of both of said bars with each other and with the intermediate needles, and thereafter to move one of said bars laterally to displace a portion of each of said loops over an adjacent 15 needle.

EMIL RICHTER.
